UNITED STATES PATENT OFFICE.

FREDERICK GARGIULO, OF NEW HAVEN, CONNECTICUT, ASSIGNOR TO THE G. & O. MFG. CO., OF NEW HAVEN, CONNECTICUT, A CORPORATION.

DESIGN FOR AN AUTOMOBILE-RADIATOR CASING.

49,142.

Specification for Design.

Patented June 6, 1916.

Application filed November 12, 1915. Serial No. 61,161. Term of patent 7 years.

To all whom it may concern:

Be it known that I, FREDERICK GARGIULO, a citizen of the United States, residing at New Haven, in the county of New Haven and State of Connecticut, have invented a new, original, and ornamental Design for an Automobile-Radiator Casing, of which the following is a specification, reference being had to the accompanying drawing, forming part thereof.

Figure 1 is a front view of an automobile

radiator casing showing my new design. Fig. 2 a top plan view of the same. Fig. 3 a view in side elevation.

I claim:

The ornamental design for an automobile radiator casing, as shown.

FREDERICK GARGIULO.

Witnesses:

CHAS. OPPE,
BENJAMIN RABINOURTZ.
